UNITED STATES PATENT OFFICE.

MARY L. THOMAS, OF EAGLE, NEBRASKA.

CURTAIN-FASTENER.

SPECIFICATION forming part of Letters Patent No. 744,819, dated November 24, 1903.

Application filed June 1, 1903. Serial No. 159,548. (No model.)

To all whom it may concern:

Be it known that I, MARY L. THOMAS, a citizen of the United States, residing at Eagle, in the county of Cass, State of Nebraska, have 5 invented certain new and useful Improvements in Curtain-Fasteners; and I do hereby declare the following to be a full, clear, and exact description of the invention, such as will enable others skilled in the art to which it applies to make and use the same.

This invention relates to curtain fasteners or hangers, and more particularly to that class wherein the curtain is hung from a pole, the object of the invention being to provide 15 a simple means by which the curtain will be held securely to the pole in such manner as to permit of easy application and removal when desired, an additional object of the invention being to provide means for holding 20 the top portions of the curtains to permit them to be caught up in festoons or for holding additional draperies at the tops of the curtains.

In the drawings forming a portion of this 25 specification, and in which like numerals of reference indicate similar parts in the several views, Figure 1 is an elevation showing a window provided with a curtain-fastener embodying the present invention. Fig. 2 is 30 a perspective view of the curtain-pole with one curtain disposed thereover ready to receive the clamping-plate, said clamping-plate being shown in raised position. Fig. 3 is a transverse section taken vertically through 35 the pole and clamping-plate and illustrating the use of the supplemental spring clamping-fingers. Fig. 4 is a view similar to Fig. 3 with the clamping-plate raised. Fig. 5 is a view partly in section and partly in elevation and showing the use of a clamping-finger when a curtain is to be draped.

Referring now to the drawings, there is 40 shown a window-frame 5 of usual construction to which the present curtain-fastening means is attached. The curtain supporting and fastening means comprises a pole 6 of usual cylindrical form, which is engaged in and supported by the brackets 7, which are attached in any suitable manner to the window-head, so as to hold the curtain-pole substantially horizontal and spaced outwardly 45 from the window-frame. The curtains

(shown at 8) are hung over the pole in the usual manner and after being properly positioned thereon are held in place by means of 55 a clamping-plate 9, which is arc-shaped in cross-section, so as to fit partly around the pole and hold the curtains securely. To hold the clamping-plate in place, arms 9' are attached to the end portions thereof and project at right angles therefrom, said arms having each their end portions offset laterally with respect to each other, and these arms are pivoted against the inner faces of the brackets at their opposite ends from their clamping- 60 plates, the pivots being so located that when the arms are swung thereon the clamping-plate will be moved into and out of position to clamp the curtains against the pole. To hold the clamping-plate yieldably in either its active or its inactive position, helical springs 10 are attached to the arms adjacent to the clamping-plate and to the brackets at the opposite sides of the pivots, so that when the clamping- 65 plate is raised to its limit from its active position the points of attachment of the springs to the arms pass vertically over the pivots of the arms, and in such movement the tensions of the springs change, the tensions being such that the clamping-plate is held yieldably, but 70 securely, in either position. When the curtain is to be clamped, the clamping-plate is lowered to rest thereon, and when the curtain is to be removed the clamping-plate is raised. To permit of draping the tops of the curtain, 75 supplemental clamping-fingers are provided and consist of spring-fingers, (shown at 12,) each of the fingers consisting of a U-shaped spring-wire having its end portions wrapped about the pins or rods 13, mounted upon the 80 clamping-plate, the extreme ends of the wires resting against the ornamental heading 14, which is carried by the clamping-plate, so as to hold the spring-wire of the fingers under 85 such tension as will hold the lower ends of the fingers yieldably against the front edge 90 of the clamping-plate.

When the curtains are to be draped, the lower ends of the spring clamping-fingers are drawn outwardly, and the curtain is engaged 95 under the spring-finger and is clamped thereby against that portion of the curtain which is disposed over the curtain-pole. The ends of the spring clamping-fingers extend or de-

pend below the clamping-plate, so that they may also exert a clamping action against the curtain-pole. When the arc-shaped clamping-plate is swung upwardly, any material 5 that is clamped between it and the pole or between the spring-fingers and the pole will be released, while any material that may be clamped between the spring-fingers and the clamping-plate will be held to the clamping-plate and raised therewith.

It will be understood that the clamping-plate may be ornamented in any suitable manner, so that it will have, in effect, the appearance of a cornice, and that modifications 15 may be made and any suitable materials and proportions used for the various parts without departing from the spirit of the invention.

What is claimed is—

1. A device of the class described comprising brackets, a curtain-pole mounted in the 20 brackets, a single clamping-plate having sup-

porting-arms pivoted to the brackets for movement of the clamping-plate into and out of position against the pole, and springs connected to the brackets and arms and arranged 25 to hold the arms with the clamping-plate in active or inactive positions.

2. A device of the class described comprising a pole, a clamping-plate mounted for movement into and out of position against 30 the pole, and spring clamping-fingers mounted upon the clamping-plate to exert clamping action thereagainst, said fingers being movable with the clamping-plate into and out of clamping relation to the pole. 35

In testimony whereof I affix my signature in presence of two witnesses.

MARY L. THOMAS.
